UNITED STATES PATENT OFFICE.

THOMAS W. GREEN, OF PHILADELPHIA, PENNSYLVANIA, ASSIGNOR TO THE
WILBRAHAM BAKER BLOWER COMPANY, OF SAME PLACE.

ROTARY BLOWER.

SPECIFICATION forming part of Letters Patent No. 674,536, dated May 21, 1901.

Application filed February 14, 1900. Serial No. 5,121. (No model.)

To all whom it may concern:

Be it known that I, THOMAS W. GREEN, a citizen of the United States, residing in Philadelphia, in the county of Philadelphia and State of Pennsylvania, have invented certain new and useful Improvements in Rotary Blowers; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to rotary blowers; and the improvement consists in the construction and arrangement of the several parts of the machine, as will be hereinafter described, and more fully pointed out in the claims. Usually in machines of this class the journal-boxes in which the impeller-shafts revolve are placed outside of the pillow-blocks that support the machine upon its foundation. This construction makes it necessary to bolt the journal-boxes upon the outer sides of the pillow-blocks without any support directly under said journal-boxes, leaving the whole weight of the impellers to be carried by the bolts that connect the journal-boxes to the pillow-blocks. As a consequence the blowers have considerable vibration and the bolts are liable to be strained and work loose, thereby throwing the shafts out of alinement, making frequent repairs necessary. As machines of this class run at a high rate of speed and are generally large and heavy, sometimes weighing as much as twenty-five tons, it is desirable to get rid of any tendency to vibrate and to make them compact and strong. To accomplish the desired results, I cast the pillow-blocks, gear-housing, and journal-boxes in one piece and of a shape that will bring said pillow-blocks directly under the journals of the impeller-shaft and place the gear-wheels that convey the power from one impeller-shaft to the other inside of the journal-boxes and close up to the heads of the impellers. Placing the gear-wheels in such close proximity to the head of the blower necessitates the provision of means to prevent the oil that is contained in the case or housing surrounding the gear-wheels from being sucked

or drawn inside of the blower and forced into the air-tubes connected therewith. I therefore form around the impeller-shafts, just inside of the gear-housing, an annular groove that connects with a way or channel leading downwardly to the outside of the blower-case. This annular groove will intercept the oil in its passage along the shaft and the downwardly inclined channel will cause it to flow outside of the machine. To insure the passage of the oil down this channel, I place across the top thereof a thin piece of steel that will act as a scraper.

In the accompanying drawings, Figure 1 is a view in perspective of my improved rotary blower, showing one end thereof in section. Fig. 2 is an end elevation of the blower, showing the end of one impeller in section, as on line *x x* of Fig. 1.

A is the outer casing, surrounding the impellers of the blower.

A' is one of the impellers inside of the casing, and *A²* the solid head on the end of the impeller.

B are the driving-shafts of the impellers.

B' are the pillow-blocks, one on each side of the blower and cast integral with the gear-housing and the journal-boxes *b*.

C is a gear-wheel on one impeller-shaft and meshing into a corresponding gear-wheel on the shaft of the other impeller.

C' is a combined gear-housing and oil-box inclosing the gear-wheels on the shafts of both impellers and cast in one piece with the pillow-block. In order that the gear-wheel *C* may run with the least possible friction, the gear case or housing *C'* is made oil-tight and kept supplied with a sufficient quantity of oil to cover the teeth in the wheel. To prevent the oil being carried from the gear-wheels *C* to the inside of the blower, I form around the driving-shaft of each impeller, between the head of said impeller and the gear-wheel, an annular groove *d*, and connect with said annular groove a downwardly-inclined oil way or channel *d'*, that extends to the outside of the blower.

e is a thin strip of steel secured across the top of the downwardly-inclined channel *d'* parallel with the driving-shaft. This steel strip may be made to extend some distance downwardly into the channel *d'* and the top

edge thereof is adjusted so close to the axle that it will act as a scraper to remove the oil from the revolving shaft and deflect it into the channel d' .

- 5 When the blower is not operating under a pressure, the annular groove d will prevent the oil in the gear-cases from being sucked or drawn into the blower, and when the blower is acting under pressure it will prevent the unclean and gritty oil contained in the gear-cases from being blown outwardly into the journal-boxes of the driving-shafts.

I have shown the groove d in the part of the head-plate or end casing A^3 that surrounds the driving-shaft; but, if desired, this part of the head-plate may be made to fit snugly around the shafts B and the annular grooves d made in said driving-shafts.

The machine being constructed as shown and described, it will be seen that the whole weight of the impellers is carried by the driving-shafts, the journals of which rest upon the pillow-blocks, and there are no bolts to become unduly strained or loosened, and thus throw the impellers out of alinement. The annular grooves d surrounding the driving-shafts being located between the gear-housing and the heads of the impellers will catch any oil sucked inwardly, and any leakage arising in the blower will find an outlet through the channel d and the gritty oil in the gear-housing will not be forced into the journal-boxes.

I have shown and described the gear-housing C' cast integral with the pillow-block B' ; but, if desired, the gear-housing may be cast separately and bolted or otherwise secured to the inner side of said pillow-block.

Having thus described my invention, what I claim as new, and desire to secure by Letters Patent of the United States, is—

1. In a rotary blower, the combination of the pillow-block B' having thereon the jour-

nal-boxes $b b$, the gear-housing C' integral with said pillow-blocks and supported thereon, gear-wheels $C C$, and the end plate A^3 , having therein the grooves $d d$, and the channels $d' d'$, said gear-wheels $C C$, being covered by the gear-housing and secured upon the driving-shafts $B B$, between the journal-boxes $b b$, and the end of plate A^3 , substantially as shown and for the purpose described.

2. In a rotary blower, the combination of the impeller-shaft B , surrounded by an annular groove, with the head-plate A^3 , having therein a downwardly-directed channel or way communicating with the annular groove and thus forming a passage-way or vent extending to the outside of the blower, substantially as shown.

3. A combined vent and oil-escape for the shafts of rotary blowers that have their gear-wheels placed between the journal-boxes and the end head-plate of the blower, said vent and oil-escape consisting of an annular groove surrounding the driving-shaft and communicating with a downwardly-directed channel in the head-plate of the blower, said downwardly-inclined channel extending to the outside of the blower, substantially as shown.

4. A combined vent and oil-escape for the driving-shafts of rotary blowers, said vent and oil-escape consisting of an annular groove surrounding the driving-shaft and communicating with a downwardly-directed channel that extends to the outside of the blower and has fixed in the top portion a scraper adapted to remove the oil from the driving-shaft and deflect it into the downwardly-inclined channel, substantially as shown.

In testimony whereof I affix my signature in presence of two witnesses.

THOMAS W. GREEN.
